[57] **CLAIM**

The ornamental design for a fishing boat outrigger brace, as shown and described.

DESCRIPTION

FIG. 1 is a front perspective view of a fishing boat outrigger brace showing my new design, the broken lines are for illustrative purposes only and form no part of the claimed design;

FIG. 2 is a bottom perspective view thereof;

FIG. 3 is a top plan view thereof;

FIG. 4 is an enlarged perspective view of the brace wire mount and tightener thereof; and,

FIG. 5 is a front perspective view thereof showing two braces mounted on a fishing boat outrigger.
